ATTORNEY.

UNITED STATES PATENT OFFICE.

JOHN FARKAS, OF DONORA, PENNSYLVANIA.

RAILROAD-TIE.

1,367,541.

Specification of Letters Patent.

Patented Feb. 8, 1921.

Application filed December 6, 1919. Serial No. 843,070.

To all whom it may concern:

Be it known that I, JOHN FARKAS, a citizen of Hungary, and resident of Donora, in the county of Washington and State of Pennsylvania, have invented certain new and useful Improvements in Railroad-Ties, of which the following is a specification.

This invention relates to railroad ties and especially to those in which no spikes for holding down the rails are necessary.

The object of this invention is the provision of a simple, inexpensive rail tie which is practically indestructible, which seldom needs to be replaced, and by the use of which a large part of the labor involved in laying railroad tracks is eliminated.

A further object of this invention is the provision of a tie in which rails can be permanently, quickly and accurately set and fastened without the use of spikes, at the proper spaced distance.

A still further object of this invention is the provision of a rail tie and fastener from which the rail may be quickly removed for repair or replacement without disturbing the tie or the road bed.

To attain these and other objects, I employ the devices shown in the accompanying drawings, in which—

Figure 1 is a perspective view of my invention showing the rails in place.

Fig. 2 is a similar view of my invention, which is shown reversed end for end from position indicated in Fig. 1, the rails being removed.

Fig. 3 is a vertical section on line 3—3 of Fig. 1, and Fig. 4 is a partial vertical section on line 4—4 of Fig. 2.

In the practical embodiment of my invention, I provide an outer channel section 1 which is arranged with the flanges 2 thereof in a vertical position. One end 3 of said channel is made solid part of the way to provide an opening for supporting bolt 4 passing therethrough. Between flanges 2 of channel 1, a second channel section 5 is provided, which is arranged with the outer web face horizontal, the flanges vertical and resting on the inner web face of channel 1.

The size of said channels is such that the inner channel 5 may slide longitudinally with ease. The upper face of channel 5 is substantially in the same horizontal plane as the upper faces of flanges 2. Said channel 5 has a solid end 6 arranged near end 3

of channel 1, said end 6 having a bolt hole 7 therein for bolt 4.

For securing rails 16 to said channels, two cuts are made in each of said channels across the upper face thereof in a direction perpendicular to the longitudinal axes of the channels, said cuts being of sufficient depth to form shoulders 8, 9, 10, 11, 12, 13, 14, and 15, in said channels, which, when rails 16 are set into said cuts, reach up above the bases of said rails. Said cuts are made wider than the width of the rail base to allow said rail to be quickly and easily set into said cuts. Said shoulder forming cuts in the channels are made preferably all of the same width and shape, and are preferably spaced apart a distance equal to the track gage.

It will be seen from the drawings that one side of said cuts is shaped to fit the lower part of the rail cross section, while the other side of the cuts is of any shape, preferably vertical, so that shoulders 8, 10, 12, and 13 are designed to snugly fit the rail. It will also be seen that while curved shoulders 8 and 10 in channel 1 Fig. 2 are on the left hand side of the cut, corresponding curved shoulders 12 and 13 in channel 5 are on the other or opposite hand, in the figure on the right hand side of the cut, in order that said shoulders may fit on opposite sides of rails 16.

To assemble the tie and lay the track, channel 5 is inserted into channel 1 until bolt 4 is just able to catch the thread in hole 7, in which position the openings between shoulders 8 and 12 and between shoulders 10 and 13 are wider than the rail width at the base, so that rail 16 may be set into said opening from above if desired. The tie being placed in position in the road bed, rail 16 is set in the opening between the shoulders with one side against shoulder 8 or shoulder 10. Bolt 4 is then tightened, whereby channel 5 is drawn farther into channel 1, until shoulders 12 and 13 are brought up tightly against the rail, the rail and tie thereby being securely locked together.

What I claim is:

In a combined rail tie and fastener, a channel, upstanding flanges on said channel, a solid end in said channel having a bolt hole therein, a second channel inverted with respect to said first mentioned channel and adapted to slide therein, a solid end in said second channel in juxtaposition to the solid

end in said first channel, a threaded bolt hole in the solid end of said second channel, both of said channels having shallow cuts across the upper faces thereof, each cut being wider than the width of the rail base, parallel curved shoulders formed by said cuts and spaced apart a distance equal to the gage of the track on each of said channels shaped to fit the rail, the curved shoulders

of one channel being opposite to those of the other channel, and a bolt inserted into said bolt holes for tightening said channel shoulders against a rail.

Signed at Donora in the county of Washington and State of Pennsylvania this 2nd day of Dec. A. D. 1919.

JOHN FARKAS.
